ABSTRACT: Mechanism comprising a line space ratchet, a paper feed lever having a curved cam surface, a cam follower lever abutting by its own weight on said cam surface and controlling the release of said ratchet, a platen drive wheel, pawl means swingably supported by the paper feed lever, said follower lever being provided with a first limit stop for limiting the movement of the pawl means and with a second limit stop for limiting the movement of the paper feed lever, whereby the paper feed lever has a clamp means cooperative with the second limit stop to prevent lifting of the follower lever. The cam follower lever is attached to a through shaft which also supports a release lever. The release lever is operably connected with a lock lever holding a line space ratchet wheel in position. Upon actuation of the paper feed mechanism and movement of the cam follower lever, the lock lever is swingable out of engagement with the line space ratchet wheel for the purpose of noiseless paper feed.

**PAPER FEED MECHANISM IN TYPEWRITERS AND
SIMILAR OFFICE MACHINES**

This invention relates to a paper feed mechanism in typewriters and similar office machines for feeding the record material such as letter sheets and the like, into a specific working position.

Paper feed mechanisms are known from the prior art in which, for the purpose of noiseless paper feeding, the release of the line space ratchet wheel is effected by rolling off a follower lever on a curved surface of the feed lever which is provided with a toothed segment. In some of these devices, the pawls which are necessary for the turning of the typing platen, are brought into engagement with the platen driving gear by means of a limit stop mounted on the feed lever, after likewise being run off on a cam member.

Furthermore, mechanisms are known wherein a rotatable feed lever having an angular shape is connected by means of a movably arranged intermediate lever with a toothed segment lever. The latter is pivotally arranged on a rocking lever which is operationally connected with the line space ratchet wheel. The feed lever, is equalized as to the length of its travel, is capable of being swung into engagement with the typing platen pinion, whereby the rocking lever, the spacing length of travel of which is limited by means of two limit stops, is fixedly attached to an axis, over which, upon actuating the feed lever, the line space ratchet wheel is stepwise rotated in a known manner.

The mechanisms working with a toothed segment and roller lever have the disadvantages that the movement limiting stops for the feed lever and pawl can only unfavorably and with difficulty be installed within the frame, that no subsequent adjustment of the limits is possible, and that additional means are required to hold the roller lever on the curved surface.

The mechanisms working with a toothed segment and movement limiting rocking lever have the disadvantage, that they do not always assure the indispensable reliability of engagement. The movement limiting stops for the feed lever and rocking lever can also only with difficulty be subsequently adjusted.

The object of this invention is to avoid the aforementioned disadvantages.

Another object of this invention is to create a mechanism which, having a minimum space requirement, makes possible a reliable, rapid and noiseless feeding of record material, such as letter sheets and the like, into a fixed working position.

In accordance with the present invention, the paper feed mechanism line space ratchet is released by means of a follower lever rolled off a cam surface of the paper feed lever. The follower lever abuts by its own weight against the cam surface of the paper feed lever. The follower lever has a first limit stop positioned on it for limiting the movement of the pawl, as well as a second limit stop for limiting the movement of the paper feed lever. Additionally, the paper feed lever is capable of being clamped by means of a clamping lip to prevent the pawl from lifting the follower lever from the cam surface.

The present invention will now be explained in more detail in an example of one embodiment, with respect to accompanying drawing, wherein:

FIG. 1 shows the lateral view of the paper feed mechanism in an unactuated position;

FIG. 2 is a lateral view of the line space ratchet wheel of the paper feed mechanism according to FIG. 1; and

FIG. 3 is the paper feed mechanism according to FIG. 1 in an actuated position.

The paper feed lever 1, operationally shaped as shown in FIG. 1, as well as the driving gear 2 for the typing platen, are pivotally supported on a common bearing bolt 3 mounted in the right-hand side portion of the carriage. The driving gear 2 engages a pinion 4 which is seated on the platen shaft 5 and connected by means of two straps (not shown) with the typing platen. A rivet 6, positioned on the paper feed lever 1, pivotally supports a shank spring 8 and the typing platen driving pawl 7 which is capable of being swung into engagement with the driving gear 2. To the right-hand side portion of the

carriage, a two-fold angle guide 9, having a curved end surface 9a, is fixed in such a manner that the pin 10, which is riveted on the pawl 7, abuts, owing to the effect of the shank spring 8, in a sliding-off position on the curved end surface 9a.

For the purpose of noiseless paper feed, a follower lever 11, which is attached on a through shaft 12 pivotally supported by both side portions of the carriage, is by means of its follower 13 in permanent contact with the cam surface 1a of the paper feed lever 1, on which the follower lever 11 abuts by its own weight.

Additionally, the follower lever 11 is provided with a limit stop 11a, having the form of a curved projection shaped for limiting the motion of the pawl 7, and with a stop pin 14 to limit the motion of the paper feed lever. When the feed lever 1 is lifted away from a rest member A, as shown in FIG. 3, a clamping lip 1b of feed lever 1 is able to clamp the stop pin 14.

On the side of the carriage opposite to the paper feed lever 1, the release lever 15 is affixed to the shaft 12. The release lever 15 acts with its face 15a on a bolt 17 positioned at one end of the lock lever 16. The lock lever 16 is pivotally supported on the lock lever shaft 18 and carries on its lever arm 16a the stop roller 19 for a locking engagement with the line space ratchet wheel 20.

The mode of operation of this machine is as follows:

Upon actuation of the paper feed lever 1, the pawl 7 initially resting on the curved end surface 9a of the angle guide 9 is moved upwardly and engages, owing to the resilience of the shank spring 8, the driving gear 2, which transmits its movement over the pinion 4 to the typing platen. In known manner the inserted sheet of paper can be seized by the movement of the typing platen and can quickly be brought into a specific operating position.

At the same time, the follower 13, following the rotating cam surface 1a of the paper feed lever 1, is raised consequently, the follower lever 11 is angularly displaced and turns the shaft 12 until the release lever 15 lifts the lock lever 16 and as a result the stop roller 19 swings out of engagement with the line space ratchet wheel 20. The driving gear 2 which is driven by the pawl 7, during the entire travel of the paper feed lever 1, thus secures the intended rotary movement of the typing platen. When the predetermined depth of insertion of the paper sheet is attained, the pawl 7 strikes with its face 7a against the adjustable limit stop 11a of the follower lever 11, and immediately after the travel of the paper feed lever 1 is stopped due to the engagement of its hook-shaped clamping lip 1b with the stop pin 14. The clamping of the clamping lip 1b is provided to prevent further lifting of the follower lever 11 when the pawl 7 impacts the limit stop 11a. Additionally, the position of the follower lever 11 can easily be subsequently adjusted by means of screws 22, 23.

Upon release of the paper feed lever 1, the same is again returned into its initial position by the force of the tension spring 21. Simultaneously the pawl 7 slides easily over the driving gear 2, until the former, owing to the running-up of the riveted pin 10 on the curved end surface 9a, is completely out of engagement with the driving gear 2.

Similarly, the roller lever 11 falls back again into its starting position and the stop roller 19 is again swung into engagement with the line space ratchet wheel 20.

The mechanism according to this invention can be installed in conventional carriages and it insures a noiseless feeding of record material as well as operational reliability of the entire system.

We claim:

1. In a typewriter and similar office machines, carriage means comprising a bearing bolt, a platen shaft and a through shaft attached in parallel alignment with each other on said carriage means, a driving gear rotatably mounted on said bearing bolt, a paper feed mechanism comprising a paper feed lever mounted on said bearing bolt, a pinion seated on said platen shaft and engageable by said driving gear, a follower lever mounted on said through shaft, pawl means pivotally attached to said paper feed lever and selectively engageable

with said driving gear, said paper feed lever provided with cam means and clamp means, said follower lever provided with cam follower means, said follower lever abutting by its own weight on said cam means, and said follower lever being further provided with a first limit stop to limit the movement of said pawl means and with a second limit stop to limit the movement of said paper feed lever whereby said clamp means clamps in a terminal position said second limit stop to prevent lifting of said follower lever.

2. The paper feed mechanism according to claim 1 wherein said first limit stop has the form of a curved projection shaped for limiting said pawl means whereas said second limit stop has

the form of a protruding pin for cooperation with said clamp means.

3. The paper feed mechanism according to claim 1, wherein said pawl means are pivotably supported on a rivet mounted on said paper feed lever, and biased by means of a shank spring.

4. The paper feed mechanism according to claim 3 further comprising an angle guide having a curved end surface for guiding said pawl means out of engagement with said driving gear and a tension spring for biasing said paper feed lever.
